UNITED STATES PATENT OFFICE.

EMILE MAERTENS, OF PHILADELPHIA, PENNSYLVANIA, ASSIGNOR TO
EDWARD SCHEPPERS AND EMILE SCHEPPERS, OF SAME PLACE.

DESIGN FOR WOVEN FABRIC.

Specification forming part of Design No. **11,560**, dated December 30, 1879; application filed December 8, 1879.
[Term of patent 3½ years.]

To all whom it may concern:

Be it known that I, EMILE MAERTENS, of Philadelphia, Pennsylvania, have produced or invented a new and original Design for a Woven Fabric, of which the following is a specification.

My design for a woven fabric is fully shown in the accompanying drawings, which represent exaggerated views of three pieces of fabric differing from each other in a certain minor detail, referred to hereinafter, but all showing the characteristic feature of the design, which comprises the stripes A A, each composed of two closely-woven bands, *a*, and an intervening open-work band, *b*, said stripes A A being separated by a space, *d*, crossed by the wefts, so as to present an appearance essentially different from the bands *b*.

The bands *a* in Figure 1 are corded, the bands *a* in Fig. 2 have a "satine" effect, and

the bands *a* in Fig. 3 present a mottled appearance, these modifications being illustrated in order to show that the character of said bands *a* may be varied without affecting the distinctive appearance of the design.

Irrespective of the colors employed, I claim—

The design for a woven fabric, said design comprising stripes A, each composed of closely-woven bands *a* and open-work bands *b*, said stripes being separated by a space, *d*, crossed by the wefts, all substantially as described, and as shown in and by the accompanying drawings.

In testimony whereof I have signed my name to this specification in the presence of two subscribing witnesses.

EMILE MAERTENS.
